YORK.

PAPER-BOX MACHINE.

Application filed September 25, 1925. Serial No. 58,678.

This invention relates to paper box machines of the variety, for example, adapted for folding a blank about a former and pressing the glued folds in place to form the box. One object of the invention is to provide a machine of this character comprising improved mechanism for manipulating the blank and for applying pressure to the glued folds to effectively set and secure 5 the same in position. More specifically stated, it is an object of the invention to provide such a machine having a moving former about which the blank is folded and comprising roll-like members arranged to 10 apply a relatively heavy pressure to the glued folds repeatedly during movement of the former in opposite directions, for securely setting the folds in the desired position. Another object is to provide a machine of the character described having an 15 improved former provided with one or more blank gripping parts operated automatically by cooperating parts on the frame for moving the gripping parts to and from position for holding the blank on the former while its glued folds or flaps are being 20 pressed and secured in place.

To these and other ends the invention resides in certain improvements and combinations of parts, all as will be hereinafter 25 more fully described, the novel features being pointed out in the claims at the end of the specification.

In the drawings:—

Figure 1 is a sectional elevation on the line 30 1^a—1^a in Figure 4, showing a paper box machine embodying the present invention;

Figure 2 is a similar view but with the parts in a different operating position;

Figure 3 is a perspective view of a paper 35 box such as made by the machine;

Figure 4 is a top plan view of the parts shown in Figures 1 and 2;

Figure 5 is an enlarged plan view of portions of the machine partly in section on the line 50 5^a—5^a in Figure 1;

Figure 6 is a view of parts shown in Figure 5 but in a different operating position;

Figure 7 is an enlarged elevation of portions of the machine partly in section on the line 55 7^a—7^a in Figure 1;

Figure 8 is a view similar to Figure 7 but with the parts in a different operating position, and

Figure 9 is a sectional detail view on the line 9^a—9^a in Figure 2.

Similar reference numerals throughout the several views indicate the same parts.

This invention is in the nature of an improvement in the invention disclosed in our 60 pending application for patent, Serial No. 601,140, filed November 17, 1922, for box making machines, and is shown in the present instance, by way of illustration, as embodied in conjunction with the machine 65 shown and described in the said application to which reference may be had for a more complete description of the machine as a whole, the present improvement relating more especially to means for holding and 70 pressing the blank on the former. The machine comprises a main frame having side portions 10 formed with seats or sills 11 on which is supported a bed plate 12 carrying mechanism for pressing the blank folds, and 75 for stripping the completed box from the former as the latter is reciprocated from above toward and from the bed plate, together with portions of the means for ejecting the stripped boxes. The former is shown 80 as a block-like member 13 fixed on the lower end of a plunger 14 carried at its upper end by mechanism (not shown) by which it is reciprocated vertically toward and from the bed plate. The mechanism for reciprocating 85 the former may be of any suitable variety such as shown in our said application and forms no part of the present invention.

Fixed to the frame 10 at the sides of the path of the plunger are cross bars 15 on 90 which are carried rails 16. Supported on the latter by any suitable means and preferably so as to be adjustable toward and from the path of the former are brackets 17 carrying vertical strips 18. These strips are curved 95 outwardly at their upper ends as at 19 and extend along and adjacent the path of movement of the ends of the former for the purpose of folding and holding the end flaps of the box during the movement of the former to initially press the glued surfaces 100 of the folds together. Similarly at the opposite sides of the former are folding strips 20, 21, respectively, mounted on cross rails 22 of the frame. It will be understood that 105 when the former is raised to its upper position, a blank is fed beneath it as described in our said application and that the former in

descending carries the blank with it between the folding means or rails described above to fold the flaps of the blank about the sides and the ends of the former as shown, for example, in Figures 1, 2 and 7 where the blank is represented at 23. The blank is preferably given a preliminary scoring along the intended lines of folding, as well understood in the art and the folding means described above are of a construction and number, such, for example, as more particularly described in our said application, requisite to the particular conformation of the blank and box to be formed therefrom. In the present instance the former carries the blank past such folding means into cooperation at the lower end of the stroke with roll-like pressing members which apply heavy and repeated pressure to the end folds or flaps to securely set the same while the former moves down and back past such members, as more fully described hereafter. The completed box is stripped from the former on the upstroke thereof by stripping means located above the pressing members, at which point the stripped box is ejected laterally from the path of movement of the former, as also described hereafter. For this purpose the folding strips 20 at one side of the former are shorter than the opposite folding strips 21, Figures 7 and 8, being discontinued as at 24 to leave space therebelow for the ejection of the completed box toward that side of the frame.

35 The former 13 is fixed adjacent the center of its upper surface to the lower end of the plunger or shank 14, as shown, and is provided by the present invention with automatically movable means for holding the blank in position thereon after it has been folded by the folding means or strips described above. Such holding means comprise, in the present instance, a pair of pivotally movable gripping parts or fingers 25 fixed on a shaft 26 mounted to oscillate in bearings 27 on the top of the former. These parts have an angular shape, as best shown in Figures 7 and 8, so that their ends project downwardly at one side of the former 50 in position to engage and hold a side of the blank after it has been folded upwardly against the side of the former, as shown in Figure 8. Figure 7 shows the gripping parts in the other or initial position. Fixed on the shaft 26 carrying the gripping parts is an arm 28 extending over the former and between this arm and the former is interposed a compression spring 29 carried in a recess 30 in the former. This spring tends 55 to rock shaft 26 to move the gripping parts resiliently into engagement with the blank. Latch means and a trip are provided for normally holding the gripping parts in the inoperative position shown in Figure 7, and 60 for releasing the same to grip the blanks

after it has been applied and folded, during the descent of the plunger as shown in Figure 8. Such means comprises, preferably, a latch plate 31 pivotally mounted in a reduced bearing portion of the plunger 14, Figures 5 and 7. A tension spring 32, fixed to the plate and to the former, tends to swing the latch plate to position a portion thereof above the arm 28 to hold the same and the gripping parts in the inoperative 75 position shown in Figure 7. The latch plate carries however an arm 33 arranged to engage at its outer end with trip means 34 in the form of a post fixed on the frame in any suitable manner and formed at its upper end with a cam portion 35 adapted to swing the arm 33, during the descent of the former, in a direction to uncover and release arm 28, so that spring 29 moves the gripping parts 25 to hold the folded side 80 of the blank. When the former rises to its uppermost position, a part 36, fixed in any suitable manner on the frame, engages the upper side of arm 28 and depresses the same as the former rises, so that latch plate 31 snaps over and again holds the gripping parts in the open position of Figure 7. It will thus be seen that this gripping means on the former is automatically operated to and from position for holding the blank 85 during each complete movement of the former. The gripping parts are arranged in the present instance on the side of the former at which the folding strips 20 are discontinued, as described above, and as 90 shown in Figures 7 and 8, so that they serve to hold the corresponding side or flap of the blank while it is released from the folding strips at the position at which the blank is stripped from the former and ejected laterally from this portion of the mechanism, and while the folding parts are shown in the present instance as applied to but one side of the former, it is obvious that additional gripping parts might be provided as 95 well for other sides of the same.

The members for applying pressure to the glued and folded ends of the blank are best shown in Figures 1, 2 and 4 in the nature of yokes 37 having curved pressing surfaces 38 in the form of sectors of pressing rolls. One such yoke is arranged at each end of the former and mounted to rock or oscillate with its pressing surface 38 in rolling engagement with the folded end flaps of the blank adjacent the lowermost position of the former. Within the sides of each yoke 37 are slidably embraced squared bearing blocks 39 oscillating on a shaft 40 stationarily supported in adjustable position as 115 hereafter described. The upper and lower side of each yoke are recessed as at 41, Figure 4, so that each yoke has an effective pair of forks, each fork supported on its corresponding block 39. Within each fork of 120 125 130

each yoke is a compression spring 42, Figure 2, bearing at one end against the corresponding block and at the other against the yoke, so that the latter are pressed resiliently towards the former and engage the same simultaneously at opposite ends with counterbalanced pressure. A tension spring 43, fixed to a bracket 44 on the frame and to a bracket 45 on the yoke, tends to raise the same to the initial position shown in Figure 1. The lower side of each yoke is provided with an abutment or bracket 46 having a facing 47 of leather or other suitable cushioning means located in the path of the bottom of the former. As the latter descends, therefore, from the position shown in Figure 1, its bottom engages the abutment 47 of each pressing member or yoke 37 to positively rock the same and produce a substantially pure rolling action between the surface 38 of the member and the folded end portions of the blank on the former. As well understood in the art, the secure setting of glued blank folds requires for best results a substantial pressure continued or repeated over an appreciable interval of time while the glue penetrates and acquires the tackey consistency requisite to its holding power. This is efficiently provided by the present invention through the heavy pressure applied by the pressing members or roll sectors 37 and through the fact that the folds are repeatedly pressed while the former is moving in opposite directions downwardly and back from its extreme lower position, adjacent which position of reverse movement it is usually driven at its lowest rate of speed. By this arrangement the glued folds are subjected to repeated pressing over an appreciable interval of time without slowing down the maximum practical rate of travel of the former, or the rate of production of the machine. The rocking of the roll sectors 37 by the engagement of the abutment portion 47 thereof by the former itself, insures accurate coordination of movement by an exceedingly simple and reliable actuating device.

The shaft 40 carrying each yoke is preferably supported for adjustment toward and from the former, to secure the desired degree of pressure against the latter and also for accommodating the machine to different sizes of former for different boxes. Accordingly the ends of each shaft 40 are fixed in sleeves 48 each threadedly engaged with a sleeve 49 rotatably mounted on one of a pair of spaced tie rods 50 mounted at their ends in supporting bearings 51 bolted as shown at the corners of the bed plate 12. Each sleeve 49 preferably has fixed on its inner end a hand wheel 52 by means of which it may be rotated on its shaft and it is positioned on the latter between the shaft bearing 51 and its collar 53. Each sleeve 49 preferably carries also a lock nut 54 at the outer side of sleeve 48, although an additional lock nut may be provided on the inner side of the latter also if desired to further secure the same in adjusted position. It is apparent from this construction that by rotating wheels 52 and sleeves 49 either of the pressing roll sectors or yokes 37 may be aligned with or set up toward or retracted from the former, for obtaining the desired pressure on the blank folds. The stresses produced during the pressing operation are transmitted to the rods 50 which are formed of a material adapted to withstand the same and relieve the stresses upon the bed plate and the frame of the machine, each sleeve 48 being securely backed up and locked after adjustment by its lock nut 54. Additional supporting or steadyng means are provided in the bearings 55 for the shafts 40 located on the latter intermediate the forks of the yokes 37. Each bearing 55 rises from a base plate 56 which may merely rest or be adjustably bolted to the bed plate 12, to assist in taking up any downward component of thrust on the shafts 40.

The means for stripping the boxes from the former are located intermediate the folding strips and pressing members 37 and above the latter and comprise in the present instance edged stripping bars 57, Figure 1, carried by the upper ends of spring strips 58 fixed at their lower ends to upright posts 59 on the base plate 56 of the bearings 55. A set screw 60 in each strip 58 provides for adjustment of the strippers 57 toward and from the path of movement of the former and blank and it is apparent from this construction that the strippers 57 are adapted to yield and permit the downward last passage of the blank but to engage the upper edges of the latter as the former rises after completion of the box, to strip the box from the former and from beneath the gripping parts 25 the engagement of which is not sufficiently positive to interfere with the stripping action. Posts 59 carry also fixed holding strips 61 in extension of the folding strips 18 for holding the blank folds during the descent of the former.

When the completed box is stripped as described it drops upon the abutment ledges 47 of the pressing members, while the latter are in their uppermost position, and is thence pushed laterally on to tracks 62 on the frame by ejecting means comprising a vertically arranged plate 63 fixed on a rod 64 sliding in a bearing 65 on the bed plate 12 and reciprocated by any suitable means such as described in our said application, in coordination with the movements of the former.

In operation, the former descends upon a blank fed beneath it and carries the same downwardly through the folding means or

strips 18, 20 and 21 surrounding the path of the former. Such folding means fold up the flaps and sides of the blank against the sides of the former and the glued portions especially are preliminarily pressed by the folding means against the former as the latter moves downwardly. After the blank is folded the gripping fingers 25 are tripped into engagement with it to hold it during the movement of the former. As the former approaches its lower limit of movement, its bottom strikes abutment ledges 47 of the pressing roll sectors at its opposite ends and rocks the same so that their pressing surfaces roll over the end folds of the blank with a substantial pressure which may be adjusted to requirements by turning the sleeves 49 carrying the supports for the pressing members. The glued blank folds are thus effectively pressed, once as the former descends and again as it rises, the pressing members remaining in continuous engagement with the folds during such pressing period, as shown in Figure 2. The glued folds are thus subjected to heavy rolling pressure counter-balanced against the opposite ends of the former, through an appreciable interval of time in the lower position of the former while the latter is descending, reversing its motion and rising. As the completed box is raised clear of the pressing members it is stripped from the former by the stripping bars 57 and ejected as described from the former path and the operation is then repeated, the gripping fingers being automatically reset to inoperative position. The construction and arrangement of the parts are such as to afford efficient manipulation and control of the blank and maximum pressing treatment of the glued folds consistent with a high rate of production.

We claim as our invention:

1. In a box making machine, a frame, a former reciprocating on said frame, folding means on the frame cooperating with said former to fold a blank about the same, and a pressing member arranged for rocking movement on the frame in engagement with the folded portions of the blank during movement of said former in opposite directions to effect repeated pressing of said folds.

2. In a box making machine, a frame, a former reciprocating on said frame, folding means on the frame cooperating with said former to fold a blank about the same, a pressing member arranged for rocking movement on the frame in engagement with the folded portions of the blank during movement of said former in opposite directions to effect repeated pressing of said folds, and a device for rocking said member operated by the movement of said former.

3. In a box making machine, a frame, a former reciprocating on said frame, folding

means on the frame cooperating with said former to fold a blank about the same, a pressing member arranged for rocking movement on the frame in engagement with the folded portions of the blank during movement of said former in opposite directions to effect repeated pressing of said folds, and an abutment on said member arranged for engagement by the former to rock said member.

4. In a box making machine, a frame, a former reciprocating on said frame, folding means on the frame cooperating with said former to fold a blank about the same, a pressing member yieldably mounted on the frame and having a rocking movement in engagement with the folded portions of the blank during movement of said former in opposite directions to effect repeated pressing of said folds, means tending to rock said member in one direction and an abutment on said member arranged for engagement by the former to rock said member in the opposite direction.

5. In a box making machine, a frame, a former reciprocating vertically on said frame, folding means on the frame for folding a blank about the former during downward movement thereof, a pressing member yieldably mounted on the frame and having a rocking movement in engagement with the folded blank portions during movement of the former to effect pressing of said folds, spring means tending to rock said member upwardly and an abutment on said member for engagement by said former to rock said member downwardly.

6. In a box making machine, a frame, a former reciprocating on said frame, folding means on the frame cooperating with said former to fold a blank about the same, and a pressing roll sector arranged for rocking movement on the frame in engagement with the folded portions of the blank during movement of said former in opposite directions to effect repeated pressing of said folds.

7. In a box making machine, a frame, a former reciprocating on said frame, folding means on the frame cooperating with said former to fold a blank about the same, a pressing roll sector resiliently mounted on the frame and arranged for rocking movement in engagement with the blank folds during movement of the former to effect pressing of said folds, and an abutment on said sector for engagement by said former to rock said sector.

8. In a box making machine, a frame, a former reciprocating on said frame, folding means on the frame cooperating with said former to fold a blank about the same, a pressing member comprising a yoke having a curved pressing surface, supporting means embraced by said yoke and supporting said pressing surface for rocking movement in

engagement with the blank folds during movement of said former and resilient means between said supporting means and yoke for pressing the yoke toward the former.

- 5 9. In a box making machine, a frame, a former reciprocating on said frame, folding means on the frame cooperating with said former to fold a blank about the same, a pair of pressing roll sectors arranged for 10 rocking movement on the frame in engagement with the folded blank portions on opposite sides of the former during movement of the same in opposite directions to effect repeated pressing of the blank folds, and devices arranged for engagement by the former to rock said sectors.

- 10 10. In a box making machine, a frame, a former reciprocating on said frame, folding means on the frame cooperating with 20 said former to fold a blank about the same, a pair of shafts on opposite sides of the path of the former, yokes embracing said shafts and mounted to slide transversely thereof and rock thereon, said yokes having curved 25 faces arranged for rolling engagement with the blank folds on opposite sides of said former during movement of the same, spring means between said shafts and yokes for pressing the latter toward the former, and 30 devices actuated by the movement of the former for rocking said yokes.

- 35 11. In a box making machine, a frame, a former reciprocating on said frame, folding means on the frame cooperating with said former to fold a blank about the same, a pressing member arranged for rocking movement on the frame in engagement with the folded portions of the blank during movement of said former in opposite directions to effect repeated pressing of said folds, and means arranged to engage the blank subsequently to pressing by said member and to strip the same from the former.

- 40 12. In a box making machine, a frame, a former reciprocating on said frame, folding means on the frame cooperating with said former to fold a blank about the same, a pressing member arranged for rocking movement on the frame in engagement with the folded portions of the blank during movement of said former in opposite directions to effect repeated pressing of said folds, and means for stripping the blank from the former located between said folding means 50 and pressing member.

- 55 13. In a box making machine, a frame, a former reciprocating on said frame, folding means on the frame cooperating with said former to fold a blank about the same, gripping means movable on the former for holding a folded blank portion, a pressing member arranged for rocking movement on the frame in engagement with folded portions of the blank during movement of said former in

opposite directions, means between said 65 folding means and pressing member for stripping the blank from the former, an ejector for discharging the box at one side of the frame.

14. In a box making machine, a frame, a former reciprocating on said frame, folding means on the frame cooperating with said former to fold and hold a blank about the same, members arranged for rolling pressing engagement with folded blank portions on 75 opposite sides of the former, blank stripping means, an ejector for discharging the box laterally below said folding means at one side of the frame, and a gripping part 80 on said former adjacent the discharge side 85 of the frame operated automatically by the movement of the former for holding the corresponding blank fold.

15. In a box making machine, a frame, a former reciprocating on said frame, folding 85 means on the frame cooperating with said former to fold and hold a blank about the same, members arranged for rolling pressing engagement with folded blank portions 90 on opposite sides of the former, blank stripping means between said folding means and pressing members, an ejector for discharging the stripped box at one side of the frame, a gripping part on the former adjacent the discharge side of the frame for 95 holding the corresponding blank fold, and cooperating parts on the frame for actuating said gripping part during movement of the former.

16. In a box making machine, a frame, a former movable on said frame, folding means on the frame for folding a blank about the former, a gripping part pivoted on the former for holding a blank fold, resilient means for moving said part to gripping 105 position, a latch on the former for holding said part inoperative, and cooperating parts on said frame for tripping said latch and for returning said gripping part to inoperative position during movement of said former.

17. In a box making machine, a frame, a former movable on said frame and provided with an operating shank, folding means on the frame for folding a blank about said 115 former, a gripping part pivoted on said former for holding a blank fold, resilient means for moving said part to gripping position, a spring actuated latch pivoted on said shank for holding said gripping part 120 inoperative, a tripping part on said frame for moving the latch to release said gripping part for movement to blank holding position, and a part on said frame for returning said gripping part to inoperative 125 position during movement of said former.

HARRY A. INMAN.

WILLIAM H. INMAN.
